CALUTRON RECEIVERS

John G. Backus, Berkeley, Calif., assignor to the United States of America as represented by the United States Atomic Energy Commission

Application May 28, 1945, Serial No. 596,225

10 Claims. (Cl. 250—41.9)

The general subject of this invention involves the separation, based on difference in mass, of minute particles, such as atoms, and especially the separation of isotopes of an element, or the separation of a portion of an element enriched with respect to a particular isotope on a scale yielding commercially useful quantities of the collected material.

The type of means or mechanism to which the invention relates is known as a "calutron," and correspondingly the method or process is known as a "calutron" method or process. The essential basic elements of a calutron include an evacuated chamber mounted in a magnetic field and containing apparatus for ionizing a polyisotope to be treated, apparatus for projecting a beam of ionized particles of the polyisotope along paths determined by the masses of the respective ions, and a target apparatus for deionizing the particles of the beam and for retaining at least one selected isotope component in a separated region from which it can be recovered.

In its presently preferred form, the calutron comprises an evacuated tank placed between the poles of an electromagnet so that the evacuated space within the tank is pervaded with a magnetic field of high flux density. Within the tank there is provided a "source unit" that includes means for supplying the polyisotope as a vapor or gas to an ionizing region, ionizing apparatus for producing positively ionized particles from the vapor, and an accelerating device maintained at a high negative electrical potential with respect to the ionizing apparatus for withdrawing the positive ions and imparting to each of them a predetermined energy in the form of substantially uniform velocities along paths generally normal to the direction of the magnetic field toward a beam defining slit in the accelerating device disposed generally parallel to the direction of the magnetic field.

The accelerated ions move transversely to the magnetic field and are constrained to travel along arcuate paths having radii that vary with the masses of the particle. By virtue of the accelerating slit construction, the paths for the ions of a given mass diverge from a median path to an extent determined by the geometry of the ionizing and accelerating devices. This divergence of the paths of travel of the ions of a given mass continues through the first 90° of arcuate travel, and then the paths converge during the next 90° and cross each other in a region of focus approximately 180° from the source unit. Thus, in effect, geometrical focusing of a ribbon-shaped stream of ions of a given mass is accomplished adjacent the 180° point, even though there is a relatively wide angle of divergence of the ions at their source.

Similarly, the ions of any other given mass travel along paths that define a ribbon-shaped stream coming to a focus at approximately 180° from the accelerating apparatus. Being composed of ions of different masses, the streams of ions of different isotopes have radii of curvature that differ by an amount dependent

2

solely upon the mass difference of their respective constituent ions. As a result, the centers of the foci of the streams of different isotopes are spaced apart by an amount approximately equal to the difference in the diameters of their respective median paths. In the case of the heavier elements, such as uranium, the difference in mass between the isotopes is not sufficient for accomplishing complete separation of the streams in which the ions of the different isotopes respectively travel, while employing a practical minimum divergence of the beam at the beam defining slit, and a plurality of overlapping streams having overlapping regions of focus are created.

A receiver is disposed within the vacuum tank adjacent the 180° foci of the isotope ions to be separated, for deionizing them and for separately collecting one or all of them as may be desired. Because of the necessary overlapping of the streams at their foci, it is impractical in one operation to separate completely the isotopes of the heavier elements, and, in practice, the separated quantities of material collected at the receiver are merely enriched with respect to a particular isotope.

The degree of isotopic enrichment that may be achieved in practice is also limited by a phenomenon known as "scattering." Probably as a result of collisions between ions, or between ions and neutral gas particles, a certain number of ions of one mass that should reach the receiver entirely outside the region of focus of the ions of a lesser mass, lose energy during their travel. After losing energy these ions of greater mass are caused to continue along arcuate paths of increased curvature, and some of them arrive at the receiver within the portion of the beam richest in a lighter component, thus increasing the contamination of the lighter component by the heavier component.

In the case of the heavier elements, the close proximity of the centers of the 180° foci of different isotope components of the beam presents still another complication affecting the isotopic enrichment obtainable in practice. The particles reaching the receiver are traveling at high speeds and tend to rebound from the surfaces they first strike, a phenomenon referred to as "sputtering." Because the particles do not necessarily rebound from a surface at an angle therewith equal to the angle of collision, sputtered material is showered in many directions from those surfaces of the receiver subjected to direct ion bombardment. As a result, the problem of retaining separated material in a region of a receiver where it first strikes, and of preventing contamination of separated material with sputtered particles from another region of the receiver, present serious difficulties. Failure adequately to handle these difficulties may result in a substantial decrease in the separation and retention efficiencies of a receiver.

For a complete disclosure of a calutron and its mode of operation, reference is made to the copending application of Ernest O. Lawrence, Serial No. 557,784, filed October 9, 1944, for "Methods of and Apparatus for Separating Materials", now Patent No. 2,709,222.

The present invention relates to that part of a calutron referred to as the "receiver," and only such parts of a calutron will be described herein as are necessary to an understanding of the present invention.

It is an object of the invention to provide an ion receiver which will retain effectively a high percentage of the ions transmitted thereto.

Another object of the invention is to provide an ion receiver which will retain ions effectively irrespective of sputtering caused when the ions strike a surface of the receiver pocket.

A further object of the invention is to provide an ion receiver which provides pocket surfaces free from direct

ion bombardment and advantageously disposed to permit deposit of deionized particles.

Another object of the invention is to provide an ion receiver which will collect the respective enriched components of a polyisotope beam in separate compartments or pockets.

Another object of the invention is to provide an ion receiver having a series of trapping walls or blades providing a corresponding series of separate compartments, each wall having one surface exposed to direct ion bombardment and the opposite wall protected from direct ion bombardment.

A further object of the invention is to provide an ion receiver having a series of ion trapping walls which are disposed at an angle to the general path of the ion beam so that one surface of each wall is protected from direct ion bombardment.

Another object of the invention is to provide an ion receiver having an ion collecting pocket and a current reading electrode adjacent thereto that is employed to monitor the beam and enable proper adjustment thereof for reception of ions by the pocket.

A further object of the invention is to provide a monitoring system for the ion beam in which a delimited portion of the beam is admitted to a current reading electrode so that the beam can be maintained in the desired adjustment by maintaining a constant current reading at the electrode.

Other objects and advantages will be apparent from the following description of a preferred embodiment of the invention as illustrated in the accompanying drawings.

In the drawings,

Figure 1 is a horizontal sectional view through a calutron tank illustrating somewhat schematically the arrangement of the source and receiver units within the tank as well as the relation of the tank to the magnet associated therewith;

Fig. 2 is an elevational view, partially in section, of the receiver unit taken as indicated by the line 2-2 in Fig. 1;

Fig. 3 is a longitudinal sectional view of the receiver unit taken in a plane indicated by the line 3-3 in Fig. 1;

Fig. 4 is a transverse sectional view of the receiver unit taken as indicated by the line 4-4 in Fig. 3;

Fig. 5 is a fragmentary view of a portion of the receiver unit taken as indicated by the line 5-5 in Fig. 4.

Referring to the drawings, Fig. 1 illustrates a calutron of the character disclosed in the Lawrence application, Serial No. 557,784, previously referred to, and which will be described generally in so far as the parts correspond to those of the above Lawrence application. The calutron includes a tank 10 which is mounted by a plurality of wheeled supports 11 on a pair of track rails 12 on one pole face 13 of the calutron magnet. The interior of the tank 10 is connected by a conduit 14 to means for reducing the pressure within the tank, including a suitably constructed diffusion pump 16 of relatively large capacity and a backing mechanical vacuum pump 17. By operation of the mechanical and diffusion pumps, the pressure within the tank 10 is reduced to a value within the desired range, which is generally of the order of from 10^{-4} mm. Hg to 10^{-5} mm. Hg.

Within the tank 10, a source unit 18 is provided for producing a beam of singly ionized positive ions to be transmitted to a receiver unit 19, the beam being indicated by the dot-dash line 21 which is disposed at the location of a median ion path within the beam. The source unit 18 includes a source block 22 carried by a stem 23 which is suitably supported by an insulator 23a on the side wall of the tank 10. The source block 22 is provided with a cavity 24 to receive a charge of the polyisotope to be treated, for example, a charge of uranium tetrachloride. The charge within the cavity 24 is heated in any suitable manner to be changed to a gas and passes into an arc

chamber 25 within the block 22 where it is subjected to an electric arc to cause ionization of the particles.

The source unit 18 also includes a pair of accelerator electrodes 26 which are disposed in spaced relation from the source block and maintained at a high negative potential with respect thereto to withdraw ions from the arc chamber 25 and accelerate the ions to form the transmitted ion beam. The accelerator electrodes 26 are supported in a convenient manner by support structure 27 within the tank 10, one of the electrodes 26 having a pivotal support 28 so that the spacing between the electrodes may be varied by means of an adjusting linkage 29 which extends through the side wall of the tank for exterior control. The above described source unit is fully disclosed in the Lawrence application, Serial No. 557,784, to which reference is made for details not shown herein.

It will be understood that the ion beam is composed of ions leaving a region of focus located between the accelerator electrodes 26 and the arc chamber 25 so that the paths of the ions as they leave the source region are distributed through a given angular divergence to either side of the median path 21 illustrated. It will be understood, of course, that there is a median path 21 for each isotopic component of the total ion beam. As previously explained, from geometrical considerations, the ion paths again converge in a region substantially 180° from the source unit to a region of focus wherein the paths of the ions again possess the same relative angularity with respect to the median path. A receiver unit 19 is located at the region of focus to receive the ions, to effect deionization, and to collect the deionized particles.

Referring to Figs. 1 and 2, the receiver unit 19 includes a cylindrical shell or casing 31 which is supported in a position generally parallel to the direction of the magnetic field by a tube 32 which extends from one end of the casing 31 and is formed in a reverse curve to provide a tube portion coinciding with an axis of symmetry of the cylinder 31 midway between the ends thereof. The tube 32 passes through an aperture in the wall 33 and a similar aperture in a closure plate 34 secured to the tank wall. The tube 32 is supported both slidably and rotatably in a combined mounting and seal structure including a plate 36, a seal 37, and a metal bellows 38. This mounting for the collector unit is of the character disclosed in said Lawrence application, Serial No. 557,784.

The receiver unit 19, as previously described, includes the cylindrical casing 31 (Figs. 3-5) which is provided near one end with an opening 40 on one side to admit ions to the interior of the casing and a smaller opening 41 at the opposite side. A third opening in the form of an elongated slot 42 (Fig. 2) is provided below the opening 40 and aligned with one side of the opening 40 for a purpose later described. A pocket structure including a series of similar pockets 43 is disposed within the casing 31 to face the opening 40 while a current reading electrode 44 is disposed therein to face the opening 41. The pockets 43 are formed of U-shaped pocket members 46 of a material resistant to ion bombardment and affording easy chemical cleansing, for example, platinum foil may be employed. At their ends, the U-shaped pocket members 46 have spacers 47 interposed between the opposed walls thereof, and the spacers 47 and pocket members 46 together with retaining plates 48 and 49 are apertured to receive securing screws 51 which have threaded engagement with the plate 49.

The plate 49 (Fig. 3) of the pocket structure is extended at one end to provide a bent portion 52 secured to a washer 53 by a screw 54. The washer 53 is rotatably seated in a cup-shaped fitting or retainer 56 of suitable insulating material which is held against endwise movement out of the casing 31 by one or more screws 57. The plate 49 (Figs. 3 and 5) is also secured by a pair of screws 58 to an insulator block 59 which is interposed between the pocket structure and the bent end 61 of the current reading electrode 44. A U-shaped metallic supporting

strap 62 is provided for the pocket structure and the current reading electrode 44, having a bent end 63, engages the end 61 of the electrode 44 and is secured therewith to the block 59 by a screw 64. The trap 62 also forms an electrode and is disposed to receive ions admitted through the slot 42. At its opposite end the strap 62 has a second bent end 63 secured by a screw 65 to an aligning disk 66 similar to the disk 53 and seated in a similar cup-shaped retainer 67. The retainer 67 is seated against a centrally recessed end plug 68, which is secured within the casing 31 by a series of screws 69 and houses a flanged insulating plug 70. The plug 68 (Fig. 3) is provided with a radial recess 71 which is enlarged at its outer end to receive the supporting tube 32.

In addition to its supporting function, the tube 32 provides a conduit for a pair of electrical leads 72 and 73 enclosed in suitable glass insulators 74. The lead 72 extends through a suitable passage in the insulating plug 70 to the screw 65 to provide the electrical lead from the electrodes 44 and 62. The lead 73 also extends through a suitable passage in the insulating plug 70, and then through an insulating fitting 76 in the aligning disk 66 and thence to one of the securing screws 51 of the pocket structure. The leads 72 and 73 extend to suitable meters 77 and 78 (Fig. 1).

By virtue of the offset or reverse curve construction of the supporting tube 32, the receiver unit can be rotated through 180° to present either the opening 40 or the opening 41 for admission of ions into the receiver structure. During focusing of the beam to obtain steady operation, the opening 41 will be presented so that the ions are admitted therethrough to the electrode 44. The width of the opening 41 is selected with respect to the total width of the beam in its plane of sharpest focus, and the opening 41 is located so as to admit the beam portion of greatest density. In the present instance, the opening 41 has a width equivalent to 3 mass units and is located to receive the maximum number of ions for such width. In this way, the current flow resulting from deionization of the particles impinging on the electrode 44 can be maximized by appropriate adjustment of the magnetic field strength and the accelerating voltage to obtain proper beam focus for reception.

When this condition obtains, the receiver unit can be rotated through 180° to present the opening 40 to the ions so that the pockets 43 will receive and retain the material as deionized particles. The width of the opening 40 in the present instance is selected to be equal to or exceed the total width of the beam in its region of sharpest focus. Considering the beam with respect to the isotopes 234, 235, and 238 of uranium, a width corresponding to 6 mass units would be appropriate. It will be understood, of course, that the opening 40 as shown in Fig. 2 does not extend for the full depth of the beam in the direction of the magnetic field, and that a portion of the beam also impinges upon the casing 31 wherein the slot 42 is formed, so that ions are simultaneously admitted through the openings 40 and 42. This enables reading of current to the electrode 62 during reception of ions by the pocket structure 43, the opening 42 being so related to the opening 40 that it receives the U²³⁸ ions, i. e., the densest portion of the beam. Thus, after appropriate focusing of the beam by use of the opening 41 and the electrode 44, proper beam focus can be maintained during reception by maintaining a maximum current on the electrode 62.

By virtue of the rotative mounting of the respective aligning disks 53 and 66 in their associated collars 55 and 57, the pocket structure, including the pockets 43, can be rotatably adjusted upon assembly within the casing 31 so that the series of walls formed by the adjacent pocket members 46 will present the desired angle to the oncoming ions. This angle should be equal to or greater than the maximum angular divergence of ions from the median or center ion path as permitted by the

conditions obtaining at the source, including the spacing of the accelerating electrodes from the source block, the width of the slot in the source block from which ions are withdrawn, and the spacing apart of the accelerator electrodes from each other.

As shown in the drawings, for example, Fig. 4, an angle of approximately 10° is formed between the walls of the pockets 43 and the median ion path 21. Thus, with this angular relation of the walls of the pockets 43, the receiver is adjusted for an angular divergence of the ion beam from the source of ±10° or less. In this fashion, the wall surface 81 of each wall is subjected to direct ion bombardment while the opposite wall surface 82 is free from such direct ion bombardment so that material which impinges upon the wall surface 81 and is reflected or sputtered therefrom can deposit upon the wall surface 82 in each pocket.

Because the number of pockets provided covers the entire spectrum of isotope components present in the beam, the material collected in the respective pockets 43 will reflect the enrichment of the respective components in the different portions of the beam.

While there has been described what is at present considered to be the preferred embodiment of the invention, it will be understood that various modifications may be made therein and it is intended to cover in the appended claims all such modifications as fall within the true spirit and scope of the invention.

What is claimed is:

1. In a calutron having a source unit for transmitting an ion beam with ions traversing paths divergent to either side of a median ion path and means for causing convergence of said ion beam in a region of focus, an ion receiver disposed in a region of focus of said ion beam and having a series of similarly disposed ion trapping walls in the path of the beam, with each wall in an acute angular relation to the median path of the ion beam at least as great as the amount of said divergence.
2. In a calutron having a source unit for transmitting an ion beam to a target region, an ion receiver disposed in said target region and having a series of ion trapping walls disposed at an acute angle to the path of the beam to expose one surface only of each wall to direct ion bombardment.
3. In a receiver for a calutron ion beam, an ion collector comprising a series of substantially parallel ion trapping walls disposed at an acute angle to the path of the beam to expose one surface only of each wall to direct ion bombardment.
4. In a receiver for a calutron ion beam, an ion collector comprising a collecting pocket structure having a plurality of adjacent ion trapping walls in said pocket structure, each of said walls being disposed at an acute angle with respect to the beam to expose one surface thereof to direct ion bombardment and to protect the other surface thereof from such direct ion bombardment and thereby provide for retention of sputtered material on said protected surfaces.
5. In a receiver for a calutron ion beam, an ion trapping pocket having a surface exposed to the ion beam and another surface opposed to said first surface and protected from the ion beam to receive sputtered material from said first surface.
6. In a receiver for a calutron ion beam, a collecting unit comprising a pair of adjacent walls disposed in the path of the beam having opposed facing surfaces, one wall surface being exposed to direct ion bombardment and the opposed wall surface being protected from ion bombardment to receive sputtered material from said first wall surface.
7. In a receiver for a calutron ion beam composed of ions whose paths in the region of reception vary through a given angular divergence from a median ion path, a collecting member disposed in the path of said ion beam in said region of reception and at an acute angle to said

median ion path at least as large as the maximum angular divergence of said ions from said median ion path.

8. A receiver for a calutron ion beam comprising a housing having an opening disposed to admit a selected portion of said ion beam and a series of similar pockets mounted within said housing to collect ions passing through said opening.

9. In a calutron having means for establishing an ion beam with ions traversing paths divergent to either side of a median ion path and means for causing convergence of said ion beam in a region of focus, an ion receiver comprising a collecting pocket and an electrode having a surface disposed adjacent the region of focus for intercepting another portion of the ion beam.

10. In a calutron having means for establishing an ion beam with ions traversing paths divergent to either side of a median ion path and means for causing convergence of said ion beam in a region of focus, an ion receiver comprising a collecting pocket for receiving a portion of the ion beam and an electrode having a surface for intercepting another portion of said ion beam, said electrode being disposed to receive a similar but more delimited portion than that received by said pocket.
